ADJUSTABLE DOOR STAY

Sixten-Shogran, Kansas City, Kans.

Application March 29, 1943, Serial No. 481,042

5 Claims. (Cl. 16—138)

This invention relates to improvements in adjustable door stays and has particular reference to a door brace which braces the door structure to the door jamb.

The present door braces now in use contemplate the straightening of the door frame by attaching a brace to spaced apart parts of the door frame then adjusting a pull bar which squares the door frame. This type of door brace does not correct the adjustment of the door to the door jamb which often obtains.

The principal object of the present invention is the provision of structure which will maintain the door in proper relation to the door jamb and also corrects the sag of the outer portion of the door frame.

A further object of the invention is the provision of a door brace adapted to interconnect the free edges of a hinged door, to the door jamb whereby the door brace serves to partially support the door in its swinging operation.

Another object of the present invention is the provision of a hinged door adjusting means having an adjustable stay rod having one of its ends secured to the free edge of the door and its other end secured to the door supporting jamb.

Other objects are simplicity and sturdiness of construction, ease of adjustment and adaptability for use on extremely large and heavy doors.

Reference will now be had to the drawing wherein:

Fig. 1 is an elevational view of a hinged door provided with an adjustable door stay embodying this invention.

Fig. 2 is an edge view of the door jamb with hinge members in position and the door removed.

Fig. 3 is an enlarged fragmentary view partly in section of the adjusting portion of the stay.

Fig. 4 is a sectional view taken on line IV—IV of Fig. 3.

Fig. 5 is an enlarged sectional view taken on line V—V of Fig. 1.

Throughout the several views like reference characters refer to similar parts and the numeral 10 designates a door jamb, such as the jamb of a double garage door whereon is mounted the door 12 by means of hinges 14. These garage doors are relatively heavy and subjected to severe strains and stresses which cause them to sag and become out of true with the door jamb.

The door adjusting means 16 is secured by means of anchor means 18 to the free edge of the door preferably near the bottom side, and by a hinge means 20 to the door jamb so that the tension rod 22 will be disposed obliquely to

the door structure for the purpose of raising the outer door structure.

The anchor means 18 comprises a bolt 24 mounted in a sleeve 26 which is snugly fitted through a hole 28 formed through the lower free corner of the door. Bolt 24 extends beyond the face of the door and is provided with washers 30 between which is positioned the eye 32 of tension rod 22 to engage bolt 24.

The hinge means 20 includes a hinge plate 34 having spaced apart ears 38 which are axially bored at 38 and 40 respectively to receive the threaded pintle 42. Referring to Fig. 3 it will be noted that the bored hole 38 is threaded to engage the threaded portion of the pintle and that the other ear is plain bored to receive the plain section 44 of the pintle.

Hinge member 20 is adapted to be securely fastened to the jamb 10 by means of screws 46 and when so fastened the pintle 42 will be in axial alignment with the axes of door hinges 14 so that the relation of door securing means will maintain a constant position relative to the door regardless of the position of the door on its hinges.

A movable hinge member 48 is vertically adjustable on pintle 42 by means of nuts 50 which operatively engage the threaded portion of the pintle and have cylindrical bearing hubs 52 which are positioned in the hole 54 formed through the body of hinge member 48. When so positioned the hinge member is free to rotate with the door on hubs 52. The upper end of tension rod 22 is provided with an eye 54 which passes through hole 56 formed through the ear 58 of hinge member 48.

When it is desired to correct the position of the door the nuts 50 are adjusted along the pintle to raise or lower the hinge member thereby causing the desired adjustment of the door relative to the door opening. To insure free swinging of the hinge member 48 with the door a U-shaped strap 60 is secured to the door by means of screws 62 to limit the movement of said hinge member relative to the door.

Closed nuts 64 are provided at each end of the pintle to lock the pintle in position and to produce a finished hinge. This door adjusting means not only corrects the relative positions of the door parts but also serves to assist the hinges in the support of the door and maintains the door in proper position relative to the door jamb.

While in most instances it is the purpose of the structure to place the door hinges and the pintle

42 in axial alignment, however under certain conditions it might be desirable to slightly offset said pintle from the direct alignment with the hinges to cause a resultant movement of the door structure as the door is moved on its hinges.

While but one application of the invention has been shown it is to be understood that many different applications of the invention might be made and also more than one of the adjusting means might be combined on a single door to meet the required needs.

It is very apparent that many minor changes might be made in the general structure of the device without departing from the spirit of the invention.

What is claimed as new is:

1. An adjusting means for a door hinged to a jamb comprising a tension rod connected to the lower free edge portion of the door and to an ear of a hinge member having a pintle and carried by said jamb adjacent the top portion of said door and disposed with its pintle in axial alignment with the hinges of said door and means to vertically adjust said ear on the pintle of said hinge member whereby the tension rod is adjusted to vertically adjust the outer edge of said door, and means carried by said door to maintain said ear in operative relation with the door.

2. An adjusting means for a door hinged to a door jamb comprising a tension rod secured at its one end to the lower free edge portion of said door and at its other end to the free leaf of a hinge mounted on the door jamb above said lower edge portion of said door, said hinge having a threaded pintle, fixed in the hinge in axial alignment with the pintles of the door hinges, on which said leaf is carried, and a nut operatively mounted on said threaded pintle to raise or lower said leaf, whereby the tension rod is adjusted to vertically adjust the outer edge of the door.

3. An adjusting means for a door hinged for horizontal oscillation to a jamb comprising a rigid tension rod connected to the free edge portion of the door and extending diagonally upwardly therefrom to an ear of a hinge member carried by said jamb, said hinge member having a pintle disposed in axial alignment with the axes of the hinges of said door, and means to vertically adjust said ear on the pintle of said hinge member whereby the tension rod is adjusted to vertically adjust the outer edge of said door.

4. An adjusting means for a door hinged for horizontal oscillation to a door jamb comprising a tension rod pivotally mounted at its one end to the lower free edge portion of said door and secured at its other end thereabove to the free leaf of a hinge having its other leaf securely attached to said door jamb, said attached leaf having a pintle rigidly secured thereto in axial alignment with the axis of oscillation of said door to carry said free leaf, and means to vertically adjust said free leaf on said pintle, whereby said tension rod is moved to vertically adjust the outer edge of the door.

5. An adjusting means for a door hinged for horizontal oscillation to a door jamb comprising a tension rod secured at its one end to the lower free edge portion of said door and secured at its other end adjacent the top of the door to the free leaf of a hinge having its other leaf securely attached to said door jamb, said attached leaf having a pintle rigidly secured thereto in said alignment with the axis of oscillation of said door to carry said free leaf, and means including threads and a nut to vertically adjust said free leaf on said pintle whereby said tension rod is moved to vertically adjust the outer edge of the door.

SIXTEN SHOGREN.
